(57) **CLAIM**

The ornamental design for a mobile phone case as shown and described.

DESCRIPTION

FIG. 1 is a perspective view of a mobile phone case showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an exploded perspective view thereof showing the components of the mobile phone case separated for clarity of disclosure.

The broken lines depict portions of the mobile phone case that form no part of the claimed design.
